UNITED STATES PATENT OFFICE.

THOMAS EDWARD BEAGHAN, HUBERT BIRD REID, AND JACOB H. BEST,
OF SHENANDOAH, VIRGINIA.

RELIEF-VALVE FOR LOCOMOTIVES.

No. 842,060.

Specification of Letters Patent.

Patented Jan. 22, 1907.

Application filed February 3, 1906. Serial No. 299,318.

To all whom it may concern:

Be it known that we, THOMAS EDWARD BEAGHAN, HUBERT BIRD REID, and JACOB H. BEST, citizens of the United States, and residents of Shenandoah, in the county of Page and State of Virginia, have invented a new and Improved Relief-Valve for Locomotives, of which the following is a full, clear, and exact description.

This invention relates to locomotive attachments. While the invention may be applied to the cylinders of locomotives using slide-valves, it is especially applicable where piston-valves are employed.

The object of the invention is to provide an arrangement which will operate to prevent compression in the ends of the cylinders or steam-chest when the pistons are moving freely therein and without steam and under such conditions as arise when the locomotive is drifting or running freely without steam, as in stopping or in going down a grade.

The invention consists in the construction and combination of parts to be more fully described hereinafter and particularly set forth in the claims.

Reference is to be had to the accompanying drawings, forming a part of this specification, in which similar characters of reference indicate corresponding parts in all the figures.

Figure 1 is a side elevation of the cylinder and adjacent parts of a locomotive with which our invention is employed. Fig. 2 is a vertical section taken through a relief-valve which constitutes a part of the invention and taken in a plane parallel with the axis of the cylinder. Fig. 3 is a vertical section taken through the lower portion of the relief-valve shown in Fig. 2, and taken in the plane of the line 3 3 of Fig. 1—that is, at right angles to the axis of the cylinder—and Fig. 4 is a plan of the relief-valve.

Referring more particularly to the parts, 1 represents the front and lower portion of the boiler, to which the usual cylinder-castings 2 attach on each side. This cylinder-casting is formed below into a cylinder 3 and above into a steam-chest 4 for the accommodation, respectively, of a piston having a piston-rod 5 and a piston-valve having a stem 6.

In applying our invention in each of the

heads 7 of the cylinder 3 we provide tubular thimbles 8, one of which is illustrated in Fig. 2. The inner extremities of these thimbles are threaded into the heads, as will be readily understood, and their outer extremities are provided with similar threads 9, so as to enable the attachment of relief-valves 10, one valve being attached to each thimble, as shown most clearly in Fig. 1. The construction of one of these valves is very clearly shown in Figs. 2 and 3. It has a substantially cylindrical body 11, having a vertical central axis, and from this body a hub 12 projects laterally, which screws onto the threads 9 and opens communication between the interior of the body 11 and the interior of the cylinder 3.

The upper portion of the body 11 is formed into a contracted neck 13, beyond which an expanded head 14 is formed, the said head being provided with a plurality of perforations 15, so that it constitutes a rose-nozzle. At its lower end the neck 13 is provided with a conical counterbore 16, which constitutes a seat for a plunger or plug 17. This plug has a cylindrical body 18, which is of reduced diameter with respect to the body 11, as shown, so that an annular steam-space 19 is formed thereabout, as will be readily understood. The lower extremity of this body is enlarged into a head 20, which fits nicely in the bore of the body 11 and is preferably provided with packing-rings 21, as shown.

The upper extremity of the plug 17 is formed into guide-wings 22, which project upwardly into the bore of the neck 13 and constitute guides which assist the seating of the plug when it moves upwardly to its seat. The lower extremity of the body 11 of the valve is closed by a removable head 23, which preferably makes threaded engagement therewith, as shown. In this head there is mounted centrally a stem 24, which is provided with a thread 25, making a threaded engagement with the head 23, which enables the body of the stem to be adjusted in and out, as will be readily understood. Upon the threads 25 a jam-nut 26 is provided, which may be screwed up tight against the under face of the head 23 in a well-understood manner. The outer extremity of the stem 24 projects as shown and

is provided with a bolt-head 27, which facilitates the adjustment of the stem by means of a wrench.

The lower portion of the plug 17 is formed with a tapered bore 28, (indicated in dotted lines in Fig. 2,) so that an elevated end face 29 is provided. The stem 24 just described projects into this bore 28, and its extremity lies a short distance from the face 29. It should be understood that this stem 24 constitutes an adjustable stop to limit the downward movement of the plug. It has also another function, which will be described more fully hereinafter.

15 As indicated in Fig. 3, the head 23 is provided with a laterally-projecting nipple 30, which communicates through a duct 31 with a chamber 32, formed within the body 11 below the plug. This nipple 30 is preferably 20 substantially horizontal, and at a suitable point in its lower side we attach a drip-cock 33.

The valves 10 are attached at the heads of the cylinder, as shown, so that the nipples 30 project outwardly or toward the side of the 25 locomotive. To these nipples 30 we attach branch pipes 34, which lead upwardly and connect, by means of a suitable T, with a main pipe 35. This pipe extends upwardly over the steam-chest 4, at which point it is 30 provided with a suitable globe-valve 36. Beyond this globe-valve it passes into the interior of the cylinder-casting and communicates with the live-steam port, which leads from the dry pipe to the steam-chest.

35 With the construction described it should be understood that when steam is admitted to the under sides of the plugs 17 in the chambers 32 it will operate to hold the plugs 17 upwardly and upon their seats 16. This is 40 the normal condition when the engine is running under steam. When the engine is to be allowed to run freely, as on a downgrade or when coming to a stop, when the throttle is closed to shut off steam from the cylinder, 45 the plugs 17 are no longer supported by the steam-pressure and fall by gravity away from their seats. In this way communication is opened through the thimbles 8 and the rose-nozzles 14 with the outer air. Hence as the 50 piston reciprocates within the cylinder it does so with perfect freedom. In this way no compression or rarefaction of the air or exhaust-steam within the cylinder can take place. As the steam-chest 4 is in communication with the cylinder 3 through the usual steam-ports, it follows that the condition of the air within the steam-chest would become substantially the same as that in the cylinder, and in this way compression in the 55 steam-chest is always prevented. This is highly desirable, as it relieves the valve-stem 6 and valve-gear of severe strains to which they might otherwise be subjected.

In case the pipe connections 34 35, leading 60 to the relief-valves, should become broken

the relief-plugs 17 may be held against their seats by means of the adjustable stems 24 by adjusting the same inwardly a sufficient amount. In this connection it should be understood that the inner extremity of the 70 stem will advance until it engages the face 29 when the plug is upon its seat. From this arrangement in case of the failure of the pipe connections the locomotive may still be maintained in substantially good running order. 75

In case of a breakdown affecting one cylinder the globe-valve which admits steam to that cylinder will be closed, and the engine can proceed on one cylinder. There is no 80 danger of the relief-valves freezing by reason of the drip-cocks 33.

Where an engine fitted with our attachment is standing in a roundhouse, there is no 85 danger of the engine starting accidentally, as they sometimes do by reason of a leaky throttle-valve. It being understood that the plugs 17 would be in a depressed position when the engine was standing, communication would be opened from the cylinders, so 90 that any steam that escapes thereto would pass out into the atmosphere without tending to collect under pressure.

The relief-valves are adapted to be used with four-cylinder tandem and cross-compound locomotives, and in this instance the valves are connected to the low-pressure cylinders. The use of the relief-valves tends to increase the life of the piston-packing, because they prevent back pressure. 95

Having thus described our invention, we claim as new and desire to secure by Letters Patent—

1. In combination, an engine-cylinder, a relief-valve having a body with a seat formed therein, a plug movably mounted in said body and adapted to rest against said seat, said valve having a chamber beyond said plug, means for admitting live steam to said chamber, and means for opening communication from said cylinder to said body between said seat and said chamber whereby when said plug is unseated the interior of said cylinder may communicate with the atmosphere. 105

2. A relief-valve consisting of a body having a seat, a plug movably mounted in said body and having a substantially cylindrical body with a shoulder normally resting against said seat, said body having an inlet-hub adapted to admit steam to the space around said plug, said body having a steam-chamber beyond the end of said plug whereby steam-pressure in said chamber will hold said plug against said seat. 110

3. An engine-cylinder in combination with a relief-valve having a body in communication with the interior of said cylinder, said valve-body having a seat formed therein, a plug having a substantially cylindrical body 115

120

125

130

5 mounted in said valve-body, said plug having a shoulder normally resting against said seat, said valve-body having a chamber adapted to receive steam-pressure to hold said plug on said seat.

10 4. In combination, an engine-cylinder, relief-valves mounted in the heads thereof and communicating with the interior of said cylinder, said relief-valves having reduced necks in the upper portions thereof and expanded perforated heads therebeyond, plugs mounted respectively in said valves and having guide-rings received in said necks, said valves presenting seats in the lower portion 15 of said necks to receive said plugs, said plugs having heads guided in said valves, means for admitting steam to the under side of said plugs, and adjustable stops for limiting the downward movement of said plugs.

20 5. A relief-valve for a locomotive-cylinder, having a substantially cylindrical body with a hub communicating with the interior thereof, said body having a contracted neck

and an expanded perforated nozzle therebeyond, a plug having a head guided in the 25 lower portion of said body and adapted to come upon said seat, said plug having guide-rings formed at the upper extremity thereof lying within said neck, a head for said body, an adjustable stem passing through said head 30 and constituting a stop for limiting the movement of said plug, said body having means for admitting steam to the interior thereof.

In testimony whereof we have signed our 35 names to this specification in the presence of two subscribing witnesses.
